Primary Examiner — Michael C Stout*Assistant Examiner* — Fitzgerald L Butac(74) *Attorney, Agent, or Firm* — Michael Best & Friedrich LLP(57) **CLAIM**

We claim the ornamental design for a tool, as shown and described.

DESCRIPTION

FIG. 1 is a perspective view of a tool according to the present design;

FIG. 2 is an end view of the tool of FIG. 1;

FIG. 3 is a first side view of the tool of FIG. 1;

FIG. 4 is a second side view of the tool of FIG. 1;

FIG. 5 is a third side view of the tool of FIG. 1; and,

FIG. 6 is a fourth side view of the tool of FIG. 1.

The broken lines show portions of a tool which form no part of the claimed design. In addition, the dash-dot broken lines are for the purpose of showing the bounds of the claimed design, and form no part thereof. The jagged, parallel broken lines represent a symbolic break in the claimed design. Anything that appears within the confines of the jagged, parallel broken lines form no part of the claimed design.
